UNITED STATES PATENT OFFICE.

JAMES H. HASTE, OF ROCHESTER, NEW YORK. ASSIGNOR TO EASTMAN KODAK COMPANY, OF ROCHESTER, NEW YORK, A CORPORATION OF NEW YORK.

PROCESS OF DEHYDRATING NITROCELLULOSE AND REDUCING THE FIRE RISK THEREOF.

No Drawing.

Application filed April 1, 1921. Serial No. 457,720.

To all whom it may concern:

Be it known that I, JAMES H. HASTE, a citizen of the United States of America, residing at Rochester, in the county of Monroe and State of New York, have invented certain new and useful Improvements in Processes of Dehydrating Nitrocellulose and Reducing the Fire Risk Thereof, of which the following is a full, clear, and exact specification.

This invention relates to the art of handling nitrocellulose between the washing operations and the plasticizing operations. One object of the invention is to provide process steps by which all harmful amounts of water may be removed from the washed nitrocellulose fibers without increasing the fire risk, such fibers being kept in a condition of comparative safety up to the time when they are incorporated into suitable compositions or dopes.

Another object of the invention is to substantially dehydrate the nitrocellulose by the use of one liquid and then wholly or partially replace such liquid by a second one which is capable of lowering the fire risk, and can, if desired, enter the final composition as an ingredient along with the nitrocellulose. Another object is to provide a novel intermediate product in the form of nitrocellulose fibers suitably protected against fire risk and capable of being readily stored and transported. Other objects will hereinafter appear.

When cellulose fibers have been nitrated, the acid is removed therefrom by thorough washing in water or aqueous solutions. But the amount of water which remains in the mass of washed fibers cannot be reduced by wringing or like mechanical means to a point where the nitrocellulose is ready for incorporation into the usual plastic compositions. If this residual moisture be finally removed by evaporation, the nitrocellulose fibers become so dry that the hazard of fire, or even of explosion, is very greatly increased, as experience has shown. In order that the nitrocellulose may be stored and transported safely, it should be kept in a wetted condition, the term "wetted" here being intended to apply to fibers that are intermingled with non-aqueous liquids as well as when wetted with water.

It has been customary to remove the

water, left after the wringing operation, by percolating a suitable liquid through the mass of fibers, the removal of the water taking place by mere displacement or absorption in the removing liquid, or by both methods acting simultaneously. After the fibers have been thus dehydrated, they are left in the condition in which they are wetted by the water-removing liquid. This remaining liquid has been depended upon to keep down the fire risk of the fibers by preventing them from becoming dry, and has customarily entered into the final compositions or dopes as an ingredient thereof along with the nitrocellulose.

Now the substances which act as water removers and at the same time are capable of lowering the fire risk and entering into the final composition are comparatively few and several of them are very expensive. I have discovered that the range of liquid substances suitable for use can be greatly increased and the expense moreover diminished by dividing the intermediate part of the process into two steps wherein two different liquids are employed. In this way each liquid does not have to have all of the properties that have heretofore been considered necessary, but each liquid supplements the other so that all of the necessary effects are produced in the process at the proper time.

The liquid used in the first or dehydrating step of the process may be one that is not desired in the final composition or dope and may in addition not be well adapted for the lowering of the fire risk. Yet it may be cheap and well adapted for the removal of the water. It should, of course, be a non-solvent of nitrocellulose under the conditions in which it is used, the nitrocellulose fibers maintaining their essential condition without gumming up into a sticky mass or solution. The liquid should also, of course, be substantially inert toward the nitrocellulose during the time that it is in contact therewith, that is, it should not injuriously re-act chemically with the fibers or induce the lowering of the nitrogen percentage in the latter. Preferably this liquid is miscible to a useful extent with water, so that it can act both by displacement and absorption in the dehydrating step. If this liquid is quite volatile at ordinary temperatures and pressures, it is not a controlling

disadvantage, because the second step of my process may take place before the fibers have dried to a dangerous extent. The water removing or dehydrating action is carried, in the preferred form of my invention, only to the point where the undesirable moisture is removed, because a small amount of moisture may enter with the ingredients into the final composition or dope without impairing the latter or objects or films made therefrom. The best liquid having the above properties which I have found for the first step of my process is ethyl alcohol of low moisture content, this substance being relatively inexpensive.

The second step of my process is performed while the nitrocellulose fibers are still wet with the residue of the dehydrating liquid of the first step. The first liquid is wholly or partially (preferably the former) replaced by a second liquid which is adapted to lower the fire risk and enter into the final composition as an ingredient thereof. Preferably it is of low volatility, so that the fibers remain wetted with it over considerable periods of time and thus do not become dangerously dry during storage and transportation. It is, of course, substantially a non-solvent of nitrocellulose under the conditions of this part of the process and is likewise practically inert toward the fibers. It is desirable that it be of low combustibility and it is beneficial if it does not tend to take up moisture from the air to a harmful extent. It should likewise be sufficiently free from mineral matter, particularly when transparent film is to be produced. There are a large number of single liquid substances, or liquids which may be mixed with each other or with suitable solids, that have the characteristics desired for the second step of my process. I find that monochlornaphthalene is satisfactory for this operation. I may use the commercial form of this substance which is an almost colorless oily liquid containing small amounts of more highly chlorinated derivatives. It boils between 240° C. and 290° C.

The treatment with the dehydrating liquid and the subsequent whole or partial displacement of the latter by the fire-risk-reducing ingredient may be performed by percolating the liquids through the mass, the excess being removed mechanically. It is convenient to place water-carrying nitrocellulose in a centrifuge and to spray the former with ethyl alcohol while the apparatus is running until the desired degree of dehydration is obtained. The monochlornaphthalene may also be applied to the nitrocellulose in the centrifuge until the alcohol is displaced to the desired extent. If the monochlornaphthalene or other suitable liquid for the second step slightly absorbs in the liquid of the first step, it may

facilitate the creeping of the second liquid along the fibers of the nitrocellulose, so as to uniformly wet them throughout the mass. Any excess of the liquid is wrung out.

The nitrocellulose fibers coated or intermingled with the monochlornaphthalene or other suitable second liquid ingredient constitute a useful intermediate product which can be readily stored and transported with comparative safety and finally can be worked up into the known compositions in the usual way.

While in the preferred form of my process the dehydration is performed to the desired extent in the first step and consequently such action is unnecessary in the second step, nevertheless, in the broader aspects of my invention the dehydrating action of the first step may be supplemented by further dehydration in the second operation. In this modification the range of substances, which may be used in the second step, is not as large as in the preferred form, but a substance suitable for entering the final composition may be employed which has much less dehydrating properties than would be necessary if it were not merely supplementing the first dehydrating action.

The liquid, which removes the water in the first step, can be used repeatedly, after dehydration, when necessary, in the usual way. Any excess of the second liquid can be used again, after purification if desired.

By way of further illustration, propyl and isopropyl alcohol can likewise be used in the first step, alone or mixed with ethyl alcohol, and in the second step monochlorbenzol, tricresyl phosphate, toluol and xylol may be employed. It will be noted that these, as well as monochlornaphthalene, are substantially anhydrous, that is they do not bring in undesirable amounts of moisture into the mass or the final compositions. They are likewise substantially non-solvents by themselves at room temperature.

Having thus described my invention, what I claim as new and desire to secure by Letters Patents is:

1. The process of dehydrating nitrocellulose and reducing the fire risk thereof prior to compounding a composition thereof, which comprises treating washed nitrocellulose carrying water with a water-removing liquid which is substantially a non-solvent of nitrocellulose and then treating the nitrocellulose with a different liquid which is substantially a non-solvent by itself of nitrocellulose at room temperature and is adapted to enter said nitrocellulose composition as an ingredient thereof.

2. The process of dehydrating nitrocellulose and reducing the fire risk thereof prior to compounding a composition thereof, which comprises treating washed nitrocellulose carrying water, with a water-absorbing

- liquid which is substantially a non-solvent of nitrocellulose and is substantially inert to the latter, and then treating the nitrocellulose with a different liquid which is a 5 non-solvent by itself of nitrocellulose at room temperature, is substantially inert toward the latter and is adapted to enter said nitrocellulose composition as an ingredient thereof.
- 10 3. The process of dehydrating nitrocellulose and reducing the fire risk thereof prior to compounding a composition thereof, which comprises treating washed nitrocellulose carrying water with a water-absorbing 15 liquid which is substantially a non-solvent of nitrocellulose and then treating the nitrocellulose with a different liquid which is by itself substantially a non-solvent thereof at room temperature, is substantially free 20 from mineral matter and is adapted to enter said nitrocellulose composition as an ingredient thereof.
4. The process of dehydrating nitrocellulose and reducing the fire risk thereof prior 25 to compounding a composition thereof, which comprises treating washed nitrocellulose carrying water with a water-removing liquid which is substantially a non-solvent of nitrocellulose and then treating the nitrocellulose with a different liquid which is by itself substantially a non-solvent thereof at room temperature and is of low volatility, said second named liquid being adapted to enter said composition as an ingredient 30 thereof.
5. The process of dehydrating nitrocellulose and reducing the fire risk thereof prior to compounding a composition thereof, which comprises treating washed nitrocellulose carrying water with ethyl alcohol and then treating the nitrocellulose with a dif- 35
- ferent liquid which is by itself substantially a non-solvent thereof at room temperature and is of low volatility, said liquid being adapted to enter said composition as an 45 ingredient thereof.
6. The process of dehydrating nitrocellulose and reducing the fire risk thereof, which comprises treating washed nitrocellulose carrying water with a water-removing 50 liquid which is substantially a non-solvent of nitrocellulose and then treating the nitrocellulose with a substantially anhydrous organic liquid which is by itself substantially a non-solvent thereof at room tem- 55 perature, is chemically inert with respect thereto, and is of low inflammability.
7. The process of dehydrating nitrocellulose and reducing the fire risk thereof prior to compounding a composition thereof, 60 which comprises treating washed nitrocellulose carrying water with a water-removing liquid which is substantially a non-solvent of nitrocellulose, and then treating the nitrocellulose with a different liquid which 65 by itself is substantially a non-solvent thereof at room temperature and is of low volatility, said second named liquid being adapted to enter said composition as an ingredient thereof and being of low inflam- 70 mability.
8. The process of dehydrating nitrocellulose and reducing the fire risk thereof, which comprises treating washed nitrocellulose carrying water with ethyl alcohol to 75 remove water therefrom, and then treating the nitrocellulose with monochlornaphthlene.

Signed at Rochester, New York, this 26th day of March 1921.

JAMES H. HASTE.
